VENDING MACHINES

Harry B. Stoner, Aurora, Ill., assignor, by mesne assignments, to The Vendo Company, Kansas City, Mo., a corporation of Missouri

Application May 7, 1954, Serial No. 428,293

2 Claims. (Cl. 312—42)

The invention relates generally to improvements in vending machines and more particularly to machines of the character which are operated by the customer and which embody a plurality of novelly constructed racks for different kinds of merchandise and novel mounting means for said racks.

Vending machines of the character herein disclosed are provided with a plurality of rack units, some including a plurality of single racks and others including a plurality of dual racks, each to contain merchandise, such as cigarettes, and auxiliary rack units for match folders. These various rack units require periodic filling and it is customary to mount them in a manner that will permit easy access thereto. The filling of the racks very often consumes a considerable amount of the serviceman's time, hence limiting the number of machines which can be serviced during any given time interval. The present invention, while permitting filling of the racks in the customary manner, considerably reduces the servicing time required by the incorporation in the vending machine of novel structure that will permit empty, or partially empty, rack units to be removed from the machine and filled rack units placed therein without requiring the use of any tools. As a consequence, rack units can be prefilled and easily and quickly placed in the machine. Also, should any rack unit require replacement for any other reason, such as for example, to adapt the machine for vending a different kind of merchandise, such replacement can be accomplished easily.

It is, therefore, an object of the invention to provide, in a vending machine, a plurality of rack units that are easily and quickly removed and installed.

Another object of the invention is to provide novelly constructed merchandise racks for a vending machine.

Another object is to provide novel means to facilitate limited tilting of the merchandise rack units to facilitate filling without removing them from the machine.

Another object is to provide, in vending machines of the character described, a novel and improved structure for mounting the merchandise racks therein.

Another object is to provide novel means for controlling the dispensing of merchandise from the dual racks.

With the foregoing and other objects in view which will appear as the description proceeds, the invention consists of certain novel features of construction, arrangement and combination of parts hereinafter fully described, illustrated in the accompanying drawings, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawings a preferred embodiment thereof, from an inspection of which, when considered in connection with the following description, my invention, its mode of construction, assembly and operation, and many of its advantages should be readily understood and appreciated.

2

Fig. 1 is a front elevational view of a vending machine of the character described, showing the outside casing removed to illustrate the three rack units mounted therein.

Fig. 2 is a horizontal sectional view taken substantially on line 2—2 of Fig. 1 and showing a coin-controlled plunger release mechanism in place.

Fig. 3 is an elevational view of the right hand vertical sectional view taken along line 3—3 in Fig. 1 and showing a merchandise rack and its mountings.

Fig. 4 is a side elevational view of the dual rack unit located at the right hand end of the machine as viewed in Fig. 1, a portion of the rack unit being shown in section.

Fig. 5 is an enlarged detail sectional view taken on line 5—5 of Fig. 1, showing a dual rack and related mechanism in section, in part.

Fig. 6 is an inverted view of the dual rack unit lock mechanism, taken substantially on line 6—6 of Fig. 5.

Referring particularly to the accompanying drawings, the vending machine embodying the present invention is provided with three novelly constructed and mounted rack units 10, 11 and 12, each adapted to contain merchandise to be vended. The rack unit 10 (right hand end of Fig. 2) includes four individual dual racks while the rack unit 11 (front left hand end of Fig. 2) includes three single racks and the rack unit 12, which is located directly behind the rack unit 11, includes three single racks. Obviously, more or fewer rack units may be incorporated in a single machine and more or fewer racks may be included in each rack unit. It should be evident, therefore, that the number of racks and rack units selected for convenience of illustration and as being most practical are not restrictive in any sense.

Reference has been made heretofore to the fact that considerable time and trouble is involved in replenishing the supply of merchandise in the rack units 10, 11 and 12. This replenishing may be accomplished in the present structure without removing the rack units from the vending machine or, if desired, empty or partially empty rack units may be removed bodily with little effort and full rack units inserted. It is this feature of the apparatus disclosed which constitutes part of the subject matter of the present application.

Another feature of the rack unit structure constituting a part of the present invention is the novel means provided for automatically releasing an auxiliary rack (to be described presently) contained in each of the dual racks. The following description is therefore concerned specifically with the aforesaid structures and their mode of assembly and operation.

The vending mechanism is enclosed within a casing of any conventional construction, and inasmuch as the casing forms no part of the present invention, it has been omitted from the drawings. The various vending rack units 10, 11 and 12 are mounted in an upright position on a base structure, or chassis, generally indicated at 17. Upon referring to Figures 2 and 5, it will be observed that the chassis 17 is substantially rectangular in shape and it includes a front wall 18, a top wall portion 19 extending rearwardly from the front wall 18 and terminating short of the back of the chassis in a downwardly extending wall portion 21. The end walls 22 of said chassis extend upwardly and terminate above the plane of the top wall portion 19. These end walls are bridged in the back by a back wall 23 which terminates at its upper end in an inturned flange 23a.

The rack unit 10, mounted on and overlying the right hand portion of the chassis 17, as illustrated in Figures 1 and 2, includes a forwardly inclined bottom wall 24 (Fig. 5) which terminates at its front edge in a downwardly extending vertical wall 25. The wall 25 terminates short of the open bottom of the rack unit to define the opening 16 communicating with the area of the chas-

sis rearwardly of the wall 25. This space is primarily provided to receive merchandise discharged from the rack units mounted on the chassis 17. The rack unit 10 has laterally spaced vertical partitions 26 defining a plurality of dual racks 27. Each of these racks is identical in construction and function, and consequently only one will be described in detail in conjunction with the general description of the rack unit 10 as a whole, it being understood that like numerals will identify corresponding parts in each of the racks.

As is best shown in Figure 2, it will be observed that the rack unit 10 includes end walls 28 and a back wall 29, the latter extending upwardly from the inclined bottom wall 24. The end walls 28 are substantially rectangular in shape, and (referring now to Figures 4 and 5) the lower ends thereof, as well as the lower ends of the partitions 26, are suitably formed to conform to the sectional configuration defined by the inclined wall 24 and depending wall 25. The lower extremity of each end wall 28 is formed with a horizontal foot portion 33 which is seated upon the chassis top wall 19.

In Fig. 4 a forwardly extending appendage 33a is welded to each end wall 28 of each rack unit 10. Extending downwardly from each appendage 33a is a hook-like formation 33b comprising an upper shank or leg portion 34 and a lower curved or hooked portion 35 extending through a slot 36 in top wall 19 as in Fig. 5. When rack 10 is in the upright position (Fig. 5) an upper edge 35a on lower portion 35 engages the bottom surface of wall 19 so as to prevent rack 10 from tilting rearwardly. When rack 10 is tilted forwardly (Fig. 3) a corner 34c formed by the junction of a lower lateral edge 34a and a longitudinal edge 34b bears against the top surface of wall 19 so as to provide a pivot point for rack 10. When rack 10 has been pivoted to an approximately horizontal position, lower portion 35 may be withdrawn from slot 36. There is thus provided a multiple support for rack 10, one of the supports being afforded by lower lateral edge 34a, another being the seating of the foot portion 33 on the top wall 19, while a third consists of the seating of the rear margin of the inclined wall 24 on the inturned flange 23a.

As has been noted hereinabove, this rack unit is mounted for ready movement from the operative full line position shown in Figure 3, into a forwardly inclined position as illustrated in broken lines in said figure. Movement of the rack into the tilted or inclined position is accomplished while the front of the vending machine cabinet is open and for the purpose of facilitating filling of the racks 27 in said unit. When tilted forwardly, as indicated, the upper extremity of the rack unit 10 is carried forwardly of the top wall of the vending machine cabinet. This permits ready insertion of merchandise through the top of each rack 27. In the present instance the merchandise is packages of cigarettes.

In order to limit forward tilting of the rack unit 10 means is provided in the form of a link 37 (Fig. 3) having its lower end pivotally mounted at 38 to the adjacent end-wall 22 of the chassis. The upper extremity of the link 37 carries a headed pin 39, normally engaged in a slot 40 provided in a track 41 secured firmly, as by welding, to the related end-wall 28 of the rack unit 10. When the rack unit is positioned vertically, the headed pin 39 is located closely adjacent to the upper end of the slot 40. When the rack unit is tilted forwardly, as indicated in broken lines in Figure 3, the headed pin abuts the lower end of the slot 40 to thereby limit further forward tilting of the rack unit. It might be noted at this time that the hinge connection 38 mounting the link 37 includes a slot 42 adapting the link 37 to be shifted relative to the hinge connection for a purpose to be described presently.

Under certain servicing conditions it may be more practical to remove an empty or partially empty rack unit 10 from the vending machine, and to replace it with a

preloaded rack unit containing the same or different merchandise. This is made feasible in the instant structure by providing novel means whereby the link 37 may be easily and quickly disconnected from the rack unit 10, after which said unit may be lifted bodily out of the machine cabinet. In order to accomplish this, the upper extremity of the slot 40 in track 41 is formed with an enlargement as at 43 of a size to permit withdrawal of the head of the headed pin 39. Such withdrawal is accomplished only after the link 37 is shifted upwardly, which shifting is permitted by reason of the slot 42 at the hinge connection, to align the head of the pin 39 with the enlarged opening 43, whereupon the link may be pulled away from the rack unit a distance sufficient to withdraw the headed pin 39 from the slot 40. The rack unit 10 is now entirely disconnected from the base 17 except for its connection through the hook-like formations 33b. Obviously, further tilting forwardly of the rack unit beyond the broken line position illustrated in Figure 3 will enable withdrawal of lower portions 35 of hook 33b from the slots 36. The rack unit can then be lifted bodily out of the cabinet and another rack unit mounted therein through a reversal of the operations described hereinabove.

As has been noted hereinbefore, the rack unit 10 is a dual rack unit. Such a rack unit is adapted to contain racks of sufficient depth to receive throughout the greater part of their length two columns of merchandise. This is perhaps best illustrated in Figure 5, where it will be observed that one column of merchandise is contained in the forward portion of each rack, forwardly of the vertical wall 25. The second column of merchandise contained in each of the racks of the rack unit 10 is supported on the inclined top wall 24 of the chassis 17. The structure is such that when the level of merchandise in the forward portion of a rack reaches a predetermined level, the merchandise contained in the rear portion of the rack is thrust forwardly off of its supporting surface 24 into dispensing alignment with the merchandise remaining in the front portion of the rack.

In order to accomplish automatic displacement of the merchandise in the rear portion of the rack, said rack is provided with elongated inserts or auxiliary racks 44 (Figure 4), each including a back wall 45 and a side wall 46 perpendicular thereto. The upper extremity of the side wall 46 has an outwardly projecting pin 47 normally seated in the downwardly turned end portion 48 of a slot 49 provided in the related wall 27 or partitions 26 of the respective rack. A leaf spring 51 disposed between the rack unit back wall 29 and back wall 45 of the insert 44 normally tends to urge the auxiliary rack into a forwardly inclined position such as is shown in Figure 4.

The auxiliary rack 44 is, however, held out of this position so that merchandise contained therein will rest upon the inclined bottom wall 24 of the rack unit. Novel releasable latch means is provided to retain the auxiliary rack 44 in such retarded position. This means includes a latch 52 pivotally mounted at 53 on the underside of the inclined bottom wall 24. The rearwardly extending free terminal of the latch 52 normally engages in front of a tongue 54 depending from the lower edge of the auxiliary rack back wall 45, and is adapted to be released only when the level of merchandise in the front column has been depleted to locate its uppermost level below the lowermost terminal of a trigger 55.

Upon referring to Figure 5, it will be noted that the trigger 55 is held normally out of the path of the merchandise in the forward column by the presence of said merchandise. Said trigger is pivotally mounted at 56 to an arm 57 extending forwardly of the pivot 53 of latch 52. It includes a weighted tail portion 58 having an arcuate edge 59. The weight of the trigger and its complementary parts, plus the frictional engagement between the latch 52

and tongue 54, is sufficient to prevent inadvertent release of the latch 52.

When the level of the merchandise in the front column has fallen below the free terminal of the trigger 55, said trigger will rock from the position illustrated in Figure 5 into the position shown in Figure 4. When this occurs, the arcuate edge 59 of the tail portion 58 will lie in the path of a gate generally indicated at 61 (Figs. 2 and 5) which gate functions, in a manner to be described presently, to lift the trigger-latch assembly and rock the latch about its pivot 53 so as to carry its free terminal downwardly out of engagement with the tongue 54. The spring 51 immediately thrusts the auxiliary rack 44 into the forwardly inclined position shown in Figure 4. This places the auxiliary rack in position to discharge its contents into the lower or vending portion of the forward part of the related main rack.

The gate 61 consists of a relatively wide plate 62 having arms 63 at its ends. The plate 62 is substantially co-extensive with the length of the rack unit 10, and said arms 63 are pivoted, as at 64, to the rack unit end walls 28. Gate 61 is operable in response to manual manipulation of a corresponding operating handle 14 extending through the front of the machine (Figs. 1 and 2). Handle 14 is connected by conventional means to an ejector plate 15 (Fig. 2) underlying the lowermost article M in the corresponding dual rack 27 to maintain the stack in the disposition shown in Fig. 5. A pull on handle 14 will withdraw plate 15 from beneath the stack and cause the latter to drop so that article M rests atop wall portion 19. When handle 14 is returned to its normally retracted position ejector plate 15 will push lowermost article M through opening 16 to be dispensed and at the same time move under the next lowermost article to again support the stack. Other means (not shown) connect handle 14 to gate 61 so that manual manipulation of the former will cause gate 61 to rock from the rearwardly inclined position illustrated in Figure 5 forwardly into a substantially vertical position and then back to its initial position. When the vending mechanism is actuated, the gate 61 is rocked forwardly to close the vending opening 16 and then rearwardly upwardly to re-open said vending opening and permit discharge of the merchandise purchased, and at the same time its upper flanged edge 65 will strike against the arcuate end 59 of the depending tail portion 58 of trigger 55, should the trigger 55 have been released so as to be resting in the position shown in Figure 4. This contact or engagement between the flange 65 of gate 61 and the tail portion 58 lifts the trigger-latch assembly and rocks the latch 52 about its pivot 53 so as to effect its disengagement from the tongue 54. As soon as merchandise from the auxiliary rack is delivered into the vending portion of the main rack the trigger 55 is repositioned so as to no longer be effected by movement of the gate 61 during subsequent vending operations. For convenience in filling the auxiliary rack, said rack may be moved into a full forward position by raising its pivot pin 47 upwardly out of the slot 48 (Fig. 4) and then carrying it forwardly in horizontal slot 49 until its forward edge abuts the front flange on the rack unit 10. After the auxiliary rack has been filled, through the insertion of merchandise at the top thereof, the upper end of said rack is then pushed rearwardly to again locate the pivot pin 47 in slot 48. The lower end of the auxiliary rack 44 is then pushed rearwardly manually, and because the related lower portion of the rack unit is now filled with merchandise, the latch 52 will engage the tongue 54 and retain said auxiliary rack in place against the tension of spring 51. The related forward column in the rack unit 10 may then be completely filled after which the rack unit is returned to its normal vertical position.

It is believed that my invention, its mode of construction and assembly, and many of its advantages should be

readily understood from the foregoing without further description, and it should also be manifest that while a preferred embodiment of the invention has been shown and described for illustrative purposes, the structural details are nevertheless capable of wide variation within the purview of our invention as defined in the appended claims.

What I claim and desire to secure by Letters Patent of the United States is:

- 10 1. A merchandise vending machine comprising a base frame including a substantially horizontal wall portion having a plurality of slots, said wall portion having upper and lower surfaces, a rack for storing merchandise to be vended, a plurality of hook means each extending downwardly from the bottom of said rack and through a respective one of said slots and engaging said wall portion for pivotally mounting said rack for movement in a predetermined direction from a normal substantially upright position through a predetermined angular displacement to a position in which said hook means may be withdrawn from said slots, each of said hook means having retaining means for engaging said lower surface of said wall portion when said rack is in said upright position to prevent said rack from tilting in a direction opposite said predetermined direction, each of said hook means having pivotal mounting means spaced above said retaining means and bearing against said upper surface of said wall portion during said movement of said rack to pivotally support said rack during said movement, said rack having a center of gravity normally biasing said rack in said opposite direction, and means for supporting said rack in said upright position.
- 20 2. A merchandise vending machine comprising a base frame including a wall portion having a plurality of slots, said wall portion having upper and lower surfaces, a rack for storing merchandise to be vended, a plurality of hook means each extending downwardly from the bottom of said rack and through a respective one of said slots and engaging said wall portion for pivotally mounting said rack for movement in a predetermined direction from a normal or substantially upright position through a predetermined angular displacement to a position in which said hook means may be withdrawn from said slot, each of said hook means comprising a first edge portion normally engaging said lower surface of said wall portion to prevent said rack from tilting in a direction opposite said predetermined direction, a projection pivotally bearing against said upper surface of said wall portion during said movement to pivotally support said rack during said movement, and a second edge portion of said hook means extending between said first edge portion and said projection and having a recess receiving an edge of said respective slot, said rack having a center of gravity normally pivotally biasing said rack in said opposite direction, and means for supporting said rack in said upright position.
